Primary Examiner—Elizabeth A. Albert*Assistant Examiner*—Kelley A Donnelly(74) Attorney, Agent, or Firm—Ward & Olivo(57) CLAIM

The ornamental design for a cosmetic display fixture, as shown and described.

DESCRIPTION

FIG. 1 is a perspective view of a cosmetic display fixture in accordance with the present invention as shown in the present design;

FIG. 2 is a front view thereof;

FIG. 3 is a rear view thereof;

FIG. 4 is a right view thereof;

FIG. 5 is a left view thereof; and,

FIG. 6 is a top view thereof.

The broken lines shown in FIGS. 1–6 are for environmental purposes only and form no part of the claimed design.
